UNITED STATES PATENT OFFICE.

PHILIP C. P. BOOTY, OF CHICAGO, ILLINOIS, ASSIGNEE, BY DIRECT AND MESNE ASSIGNMENTS, TO M. T. DALEY, OF CHICAGO, ILLINOIS.

RECEPTACLE FOR FACE POWDER AND THE LIKE.

Application filed February 21, 1925. Serial No. 10,736.

My invention relates to receptacles for holding and dispensing face powder and the like in loose form.

One object of my invention is the provision of a receptacle which will be inexpensive to manufacture, reliable in operation, compact in construction, and pleasing in appearance and which will be well suited for holding light and heavy face powder and the like in loose form and for dispensing it in small quantities as needed.

A further object of my invention is the provision of a receptacle so constructed that the powder will be dispensed in small quantities by a pneumatic action whereby upon placing a puff close to the outlet for the powder the desired quantity of powder, upon manipulating the device, will be ejected from the receptacle with appreciable force and deposited into or on the puff.

Another object of my invention is the provision of a receptacle so constructed that it may be readily refilled with powder when the supply therein becomes exhausted.

There are many satisfactory cases of standard construction now on the market for holding rouge and powder in compact form; and another object of my invention is to provide receptacles for holding and dispensing loose powder of such construction that they may be either built into or inserted as separable units into any such standard cases whereby a very material saving may be effected in the manufacture of the complete devices because of the reduced expenditures for dies, tools, etc. which would otherwise ordinarily be required.

The invention consists in the novel arrangements, constructions and devices to be hereinafter described and claimed for carrying out the above stated objects and such other objects as will appear from the following description of certain preferred embodiments illustrated in the accompanying drawing, wherein—

Fig. 1 is a perspective view of a receptacle embodying the principles of my invention, the cover thereof being swung into open position;

Fig. 2 is a sectional view of the receptacle shown in Fig. 1, the cover thereof being in closed position;

Fig. 3 is a detail view, on an enlarged scale, of a fragmentary portion of the receptacle;

Figs. 4, 5 and 6 are sectional views of receptacles also embodying the principles of my invention but of modified construction, all being adapted to be inserted in cases of ordinary construction such as are found generally on the market for holding rouge and face powder in compact form; and

Fig. 7 is a sectional view of another modified form of receptacle.

Like characters of reference designate like parts in the several views.

Referring first to that embodiment of my invention shown in Figs. 1, 2 and 3, it will be seen that the receptacle for the powder is built into and forms an integral part of the main casing. The powder receptacle includes a cylindrical shell 10 which is offset inwardly so as to form a circumferentially extending seat 11, the top of said shell being turned inwardly and downwardly thereby providing a perimetrical overhanging flange 12. The bottom member 13 for the receptacle is provided with a flange 14 which telescopes with the shell 10. Any suitable means may be employed for securing the bottom member to the shell. In the present embodiment the flange 14 is formed with a plurality of outwardly extending protuberances 14^a which are adapted to enter bayonet grooves or slots 10^a provided in the shell 10. A cover plate 15 is disposed within the receptacle and underlies the flange 12. A volute spring 16 is interposed between the member 13 and the plate 15, said spring serving to hold the plate 15 firmly against the margin of the depending flange 12. The spring 16 may be secured to the bottom member 13 by some suitable means such as solder. By turning the bottom member 13 in the proper direction relative to the shell 10 it may be removed and, when the receptacle is inverted, a quantity of loose powder may be placed in the chamber 17 and then the bottom member replaced. Depressing quickly the plate 15 displaces suddenly the air trapped in the chamber 17 and a quantity of the loose powder is ejected from the chamber through the outlet thus provided underneath the flange 12. In the ordinary operation of the device a puff will first be placed on top of the plate 15 and the puff and plate will be depressed and released simultaneously which will cause the powder ejected from the chamber to be deposited

100
105
110

into or on the puff by the pneumatic action described. Any powder which may be ejected directly onto the top surface of the plate 15 may be readily mopped up by the puff.

In order to provide a casing attractive in appearance and at the same time keep the puff and the flange 12 and plate 15 in a sanitary condition, I prefer to provide a cover 10 for the main casing. In the embodiment illustrated, a cylindrical cap member 18 is connected by a hinge 19 to the shell 10, the bottom edge of the cap member resting on the seat 11 provided on the shell 10 when 15 the cover is in closed position. A mirror 20 may be placed inside the cap or cover member 18 and held in position by any suitable means such as a retainer ring 21.

In Fig. 4 I have shown a receptacle of 20 slightly modified construction which includes a shell 22 provided with a bottom 23 having a centrally located opening 24, the upper end of the shell 22 being turned inwardly and downwardly to provide the overhanging perimetrical flange 25. A plate 26 is disposed within the receptacle underneath the flange 25. A plate 27 of substantially less diameter than the plate 26 is also disposed within the receptacle and is adapted 25 to rest on the bottom member 23 so as to close the opening 24, an offset part 27^a of said plate normally being disposed within said opening. A volute spring 28 is disposed between the plates 26 and 27 and is 30 preferably attached to the lower plate 27 by any suitable means such as the solder 29. In making this modified construction, the bottom member 23 initially will be made separate from the shell 22 and, after the plates 26 and 27 and the spring 28 have been placed 35 within the shell, the member 23 may be secured to the shell in any desired manner, for example, by spinning or turning over inwardly the lower edge of the shell. In refilling the modified device the plate 27 is 40 pushed upwardly clear of the opening 24 and then moved laterally sufficiently to permit a fresh supply of loose powder to be introduced into the powder chamber 17 45 through the opening 24.

Referring now to the construction shown in Fig. 5, the powder receptacle thereof includes a shell member 30 having a bottom 31 formed integrally therewith. A shell member 32 surrounds the member 30 and is provided with an inwardly and downwardly extending perimetrical flange 33. The shell 30 is provided with outwardly extending protuberances 34 which are adapted to slide 50 in bayonet grooves 35 provided in the shell 32 whereby the upper and lower parts of the receptacle may be readily separated or secured together. A cover plate 35 is disposed within the receptacle and underlies the 55 overhanging flange 33, said plate normally

being held against the margin of said flange by a volute spring 36 positioned between the plate and the bottom 31. In this construction when it is desired to replenish the supply of powder the member 32 may be removed and replaced by proper movement thereof relative to the member 30.

In the construction shown in Fig. 6, the powder receptacle includes a shell 37 having a bottom 38 integrally formed therewith, the upper end of the shell 37 being turned over inwardly so as to provide an annular and slightly tapered seat 39. An annular member 40 is provided with a portion adapted to fit snugly in the seat 39, said member being formed so as to provide an inwardly and downwardly extending perimetrical flange 41. A cover plate 42 is placed within the receptacle and underlies the flange 41, said plate being held thereagainst by a volute spring 43 disposed between the plate and the bottom 38. The member 40 takes a reliable frictional grip on the seat 39 which is ample to hold the member against movement relative to the shell 37 notwithstanding the action of the spring 43 and the handling to which the device will ordinarily be subjected. When replenishing the supply of powder in the receptacle the member 40 may be lifted out of the seat 39 and afterwards replaced.

Each of the modified constructions shown in Figs. 4, 5 and 6 operates in substantially the same manner as the device first described. These modified forms are adapted to be inserted into any of the several standard cases now on the market for holding rouge and face powder in compact form. Said standard cases in general comprise a bottom section 44 and a top section 45 connected by a hinge 46, the top section having a mirror 47 held in place by a retainer ring 48.

Referring now to the modified construction shown in Fig. 7, the receptacle for the powder includes a shell 49 having an inwardly and downwardly extending perimetrical flange 50 at its top side and a bottom 51. A cover member 52 is disposed within the receptacle and underlies the flange 50, said member normally being held against said flange by a volute spring 53 positioned between the member 52 and the bottom 51. The member 52 is provided with a centrally located opening 54 which is closed by a disk 55 positioned underneath the member 52 and held in the position illustrated by a volute spring 56 positioned within the spring 53 and between the disk 55 and the bottom 51. This device operates substantially like the other devices heretofore described. During normal operation of the device the disk 55 may be considered as an integral part of the cover member 52. When it is desired to replenish the supply of powder in the receptacle, the disk 55 may be depressed relative to the member 52.

This construction will ordinarily be provided with a cover member 57 attached to the shell by a hinge 58.

In all the forms of my invention illustrated it will be noted that the margins of the cover members for the respective powder chambers project a substantial distance under the respective overhanging flanges of the respective receptacles. In practice the cover members are formed so that they fit rather loosely within the respective powder chambers. In handling the device and carrying it a quantity of powder finds its way into the space 59 between the overhanging flange and the margin of the cover plate so that upon depressing the cover plate the loose powder collected in the space aforesaid is readily ejected pneumatically into the puff or onto the upper surface of the cover plate. By employing a volute spring for holding the cover of the powder receptacle against the margin of the overhanging flange, the receptacle may be made very shallow in depth if desired; furthermore such a spring does not tend to pack the powder in the receptacle.

I do not intend to limit my invention to the details of construction shown and described, except only in so far as certain of the appended claims are specifically so limited, as it will be obvious that modifications may be made without departing from the principles of my invention.

I claim:

1. A receptacle of the class described comprising a casing having inturned flange means and cover means for said casing and underlying said flange means, one of said means being capable of movement relative to the other of said means, the parts being so arranged that upon relative manipulation of said movable means powder is pneumatically ejected from the receptacle.

2. A receptacle of the class described comprising a casing having inturned flange means and cover means for said casing and underlying said flange means, one of said means being capable of relative movement in a plane normal to that of the other of said means, the parts being so arranged that upon relative manipulation of said movable means powder is pneumatically ejected from the receptacle.

3. A receptacle of the class described comprising a casing having inturned flange means and cover means for said casing and underlying said flange means, said cover means being capable of movement relative to said flange means, the parts being so arranged that upon relative manipulation of said cover means powder is pneumatically ejected from the receptacle.

4. A receptacle of the class described comprising a casing having inturned flange

means and cover means for said casing and underlying said flange means, said cover means being capable of movement relative to and in a plane normal to that of said flange means, the parts being so arranged that upon relative manipulation of said cover means powder is pneumatically ejected from the receptacle.

5. A receptacle of the class described comprising a casing having an inwardly extending perimetrical flange, cover means underlying said flange in position to close the opening therethrough, and yieldable means for normally holding said cover means against said flange.

6. A receptacle of the class described comprising a casing having an inwardly extending perimetrical flange, cover means underlying said flange in position to close the opening therethrough, and a volute spring interposed between the bottom of the casing and the underside of said cover means for normally holding said cover means against said flange.

7. A receptacle of the class described comprising a casing having an inwardly and downwardly extending perimetrical flange, cover means underlying said flange and closing the opening therethrough, and yieldable means for normally holding said cover means against the margin of said flange.

8. A receptacle of the class described comprising a casing having an inwardly and downwardly extending perimetrical flange, cover means underlying said flange and movable in a plane normal to that of the flange and adapted when in contact with the flange to close the opening therethrough, and yieldable means for normally holding said cover means against the margin of said flange, the marginal portion of said cover means projecting a substantial distance under said flange, for the purpose specified.

9. A receptacle for face powder and the like, comprising in combination a casing having an opening in its top face, a plate underlying the opening, and means normally holding the plate yieldingly in position to close said opening, the arrangement being such that by upward and downward movements of the plate air is forced through said opening serving to carry a supply of powder from the interior of the casing about the outer edge of the plate.

10. A receptacle for face powder and the like, comprising in combination a casing having an opening in its top face, a plate underlying the opening, an annular flange extending inwardly and downwardly about said opening in convergent position with respect to said plate, and means normally holding said plate yieldingly in contact with said flange, the arrangement being such that by upward and downward movements of the

plate air is forced through said opening serving to carry a supply of powder from the casing.

11. A receptacle for face powder and the like, comprising in combination a casing provided with an opening in its upper face in the form of a ring tapered downwardly and inwardly, a plate underlying the ring and movable bodily out of contact therewith, and means normally holding the plate yieldingly in contact with the ring, the arrangement being such that by the downward movement of the plate air is forced from the casing through said ring in a current curling upwardly and inwardly about the edge of the plate.

12. A receptacle for face powder and the like, comprising in combination a casing provided with an opening in its upper face in the form of a ring tapered downwardly and inwardly, a plate underlying the ring and extending laterally a short distance beyond the lower edge of the ring about the margin of the plate, and means normally holding the plate yieldingly in contact with the ring, the arrangement being such that by a downward movement of the plate air is forced from the casing through said ring in a current curling upwardly and inwardly about the edge of the plate.

13. A receptacle for face powder and the like, comprising in combination a casing provided with an opening in its upper face in the form of a ring tapered downwardly and inwardly, a plate underlying the ring and extending laterally a short distance beyond the lower edge of the ring about the margin of the plate and held by the casing against lateral displacement with respect to the ring, and means normally holding the plate yieldingly in contact with the ring, the arrangement being such that by upward and downward movements of the plate air is forced through said ring serving to carry a supply of powder from the interior of the casing.

14. A receptacle for face powder and the like, comprising in combination a casing provided with an opening in its upper face in the form of a ring tapered downwardly and inwardly, a plate underlying the ring and extending laterally a short distance beyond the lower edge of the ring about the margin of the plate and held by the casing against lateral displacement with respect to the ring, and a volute spring normally holding the plate yieldingly in contact with the ring in centered position with respect thereto, the arrangement being such that by a downward movement of the plate air is forced from the casing through said ring in a current curling upwardly and inwardly about the edge of the plate.

15. A receptacle of the class described comprising a two-part casing, said parts being releasably secured together to form a

unitary structure, one of said parts having inturned flange means, and cover means for said casing and underlying said flange means, one of said means being capable of movement relative to the other of said means, said means being so arranged that upon relative manipulation of said movable means powder is pneumatically ejected from the receptacle.

16. A receptacle of the class described comprising a two-part casing, said parts being releasably secured together to form a unitary structure, one of said parts having inturned flange means, and cover means for said casing and underlying said flange means, said cover means being capable of movement relative to said flange means, the parts being so arranged that upon relative manipulation of said cover means powder is pneumatically ejected from the receptacle.

17. A receptacle of the class described comprising a casing having at its top an inwardly extending perimetrical flange and a separable bottom member, said member being releasably secured to said casing, cover means for the casing and underlying said flange, and yieldable means for normally holding said cover means against said flange.

18. A receptacle of the class described comprising a casing having at its top an inwardly extending perimetrical flange and a separable bottom member, said member being releasably secured to said casing, cover means for the casing and underlying said flange, and a volute spring interposed between said bottom member and said cover means for normally holding said cover means against said flange.

19. A receptacle of the class described comprising a casing having at its top an inwardly extending perimetrical flange and a separable bottom member having a flange adapted to telescope with the wall of said casing, there being a bayonet slot connection between said telescoping flange and said wall, cover means for the casing and underlying said inwardly extending flange, and yieldable means for normally holding said cover means against said flange.

20. A receptacle of the class described comprising a casing having at its top an inwardly extending perimetrical flange and a separable bottom member having a flange adapted to telescope with the wall of said casing, there being a bayonet slot connection between said telescoping flange and said wall, cover means for the casing and underlying said inwardly extending flange, and a volute spring interposed between said member and said cover means for normally holding said cover means against said flange.
